UNITED STATES PATENT OFFICE.

HARRY ADOLPH BAUER, OF NEWARK, NEW JERSEY, AND GEORGE W. CASSIDY, OF NEW YORK, N. Y., ASSIGNEES TO CASSIDY COMPANY, INC., OF LONG ISLAND CITY, NEW YORK, A CORPORATION OF NEW YORK.

DESIGN FOR A DESK LAMP.

Application filed March 6, 1929. Serial No. 30,375. Term of patent 7 years.

To all whom it may concern:

Be it known that we, HARRY ADOLPH BAUER and GEORGE W. CASSIDY, citizens of the United States, residing at Newark, county of Essex, and State of New Jersey, and at New York, county of Queens and State of New York, respectively, have invented a new, original, and ornamental Design for a Desk Lamp, of which the following is a specification, reference being had to the accompanying drawing, forming part thereof, in which—

Fig. 1 is a front view, slightly in perspective, showing our new design;

Fig. 2 is a back view, also slightly in perspective; and

Fig. 3 is an end view.

We claim:

The ornamental design for a desk lamp, as shown.

HARRY ADOLPH BAUER.
GEORGE W. CASSIDY.
